OPPOSED PISTON DIESEL ENGINES

Percy Jackson, Sunderland, England, assignor to William Doxford & Sons (Engineers) Limited, Sunderland, England, a British company

Filed Apr. 22, 1959, Ser. No. 808,120

5 Claims. (Cl. 123—65)

The invention relates to two-stroke cycle opposed piston diesel engines of the kind having an upright cylinder (or several such cylinders) in which both pistons work and in which both pistons are connected to a single crank-shaft below the engine cylinder, the upper piston being attached to a cross-beam above the cylinder which is connected to the crank-shaft by rods attached to the ends of the beam. The well known Doxford engine is one example of this kind of engine.

Engines of the above kind are commonly provided with reciprocating pumps, driven by the engine, for supplying air for scavenging. It is an object of the present invention to provide such an engine with an improved construction and arrangement of engine-driven air pump.

The invention provides an engine of the above kind having a reciprocating scavenging-air pump mounted on top of the engine cylinder, and preferably a pump on each of them when there are more than one, the pump having a piston which is attached directly or indirectly (e.g. through the beam) to the upper engine piston for movement therewith and a cylinder aligned with the engine cylinder and arranged to receive within its compass the beam during at least a part of the stroke thereof.

The pump, or pumps may be single-acting.

In one construction according to the invention the pump cylinder and piston are of rectangular form whereby the cylinder may be arranged to accommodate the beam without being of larger volume than is required to provide the necessary volume of air. For example one pair of sides of the cylinder may be slightly longer than the beam and parallel thereto and the other pair of sides may have a length less than that of the first pair but greater than the width of the beam.

Preferably the pump has an inlet valve in the top cover for the pump cylinder. It is also preferred that the engine has conduits at opposite sides of the pump cylinder leading downwardly from the pump outlet to a receiver embodied in the main engine casing around the lower part of the engine cylinder. The conduits may be cast or welded integral with the frame structure and they may lead from a pump outlet valve in the top cover for the pump cylinder.

One specific construction of an opposed piston multi-cylinder engine according to the invention will now be described, by way of example, and with reference to the accompanying drawings in which:

FIGURE 1 is a diagram showing the arrangement of one cylinder of the engine and the operating parts.

FIGURE 2 is a vertical section through one cylinder, and

FIGURE 3 is a section on the line 3—3 in FIGURE 2.

The several cylinders of the engine forming the subject of this example are of like construction and arrangement and only one cylinder with its associated parts will be described in detail. The cylinder, 10, is upright and has a set of inlet ports 11 near the bottom and a set of exhaust ports 12 near the top, the two sets of ports being covered and uncovered by the two pistons 14, 15 respectively, in well known manner. The lower piston 14, has a piston rod 16, cross-head 17 and connecting rod 18 connecting the piston to one throw 19 of the crankshaft. The upper piston, 15, is secured at its upper end to a cross-beam 20 of which the ends lie outside the compass of the engine cylinder 10. Vertical coupling rods 21 are

2

attached to the ends of the beam 20 and at their lower ends have cross-head 22 and connecting rod connections 23 to two further throws 24 of the crankshaft.

Secured to the top of the beam 20 there is a thin, plate-like horizontal pump piston 28 of rectangular form. The longer sides 28a of the piston are parallel to the length of the beam 20 and slightly longer than the beam. The shorter sides 28b are somewhat longer than the width of the main body of the beam. The piston works in a pump cylinder 30 of corresponding shape and aligned with the engine cylinder. In operation the beam 20 enters into the pump cylinder 30 during the upper part of the stroke.

Vertical guideways 31 are formed centrally in the longer sides of the pump cylinder for the reception of guide slippers 32 attached to the beam 20. The upper ends of the slippers, are in this example, level with the top face of the pump piston 28 and so, in effect, act as small lateral extensions from the piston to seal the guideways 31.

On top of the pump cylinder cover there is a chamber which is divided into two parts 34, 35 by a central vertical partition 36 which, in this example, is parallel to the beam 20. The part 34 has an opening 37 to atmosphere forming an air inlet and this part also has an inlet opening into the cylinder controlled by automatic inlet valves 38. The part 35 has outlet openings 39 from the cylinder controlled by automatic discharge valves 40. The ends of the part 35 extend over two upright ducts or trunks 41 cast in the cylinder walls and leading downwardly through further ducts 42 integral with the main engine framework into a receiving chamber 43 formed in the entablature whence the air can pass into the engine cylinder through the inlet ports 11 when uncovered by the lower piston.

Various modifications may be made in the construction described above. For instance the upper ends of the slippers 32 may be beneath the piston 28 and the latter have ears or extensions into the guideways 31 to close the latter. The partition 36 may extend transversely of the beam instead of parallel thereto.

I claim:

1. In a two-stroke cycle opposed-piston diesel engine of the kind having an upright working cylinder, an upper piston working vertically in the cylinder, a cross-beam rigidly attached to the upper piston above the working cylinder and extending radially beyond the working cylinder on opposite sides, two connecting rods rigidly attached one to each extremity of the cross-beam and extending vertically downwards outside the working cylinder, two cross-heads attached respectively to the lower ends of the connecting rods and guide means therefor and an air pump cylinder mounted over the top of the working cylinder, coaxial therewith; the provision of a vertical guideway in the wall of the pump cylinder, guide means rigidly attached to the cross-beam and engaging in the guideway and a pump piston in the form of a substantially flat plate rigidly mounted directly on top of the cross-beam to work in the pump cylinder.

2. In a two-stroke cycle opposed-piston diesel engine as claimed in claim 1 wherein the pump cylinder and pump piston are substantially rectangular.

3. In a two-stroke cycle opposed-piston diesel engine as claimed in claim 1 wherein the pump cylinder has a dimension in the lengthwise direction of the cross-beam which is greater than the length of the cross-beam and the cross-beam enters the pump cylinder during at least part of the piston stroke.

4. In a two-stroke cycle opposed-piston diesel engine as claimed in claim 1 wherein there are strengthening ribs extending across the working face of the pump piston.

5. In a two-stroke cycle opposed-piston diesel engine as claimed in claim 1 wherein there is a top cover over

the pump cylinder an inlet valve and an outlet valve in the top cover, a chamber above the top cover communicating with the outlet valve, conduits at opposite sides of the pump cylinder leading downward from the chamber and a receiver around the lower part of the working cylinder connected to the lower ends of the conduits.
